UNITED STATES PATENT OFFICE.

ADAM W. KAUFMAN, OF MILWAUKEE, WISCONSIN.

TIMER.

1,425,864.

Specification of Letters Patent. Patented Aug. 15, 1922.

Application filed July 26, 1921. Serial No. 487,653.

To all whom it may concern:

Be it known that I, ADAM W. KAUFMAN, a citizen of the United States, and resident of Milwaukee, in the county of Milwaukee and 5 State of Wisconsin, have invented certain new and useful Improvements in Timers; and I do hereby declare that the following is a full, clear, and exact description thereof.

My invention relates to timers for controlling the ignition spark of internal combustion engines, such, for example, as described in my application for patent filed April 15, 1921, Serial No. 461629.

The object of my present invention is to 15 provide a contact brush of the coil spring type, yieldable in all directions, with a guide for directing movement of the coil spring contact brush in a single plane, whereby timing of the spark is micrometrically adjusted 20 and the tendency of the coil spring brush in its contact with the cam to drag backward and forward is thus eliminated.

Other objects of my invention are to provide a one piece guide for the brush formed 25 from a blank, and adopted to be readily assembled and secured in an accurately adjusted position upon the shank portions of a brush holder.

To provide a two piece actuating cam, the 30 cam blade being formed from a single blank and detachably mounted upon the cam hub, whereby said cam blade can be renewed from time to time without removing the hub. Thus economy in production and renewability of parts is effected.

To provide means including the guide and brush holder, whereby the brush can be rotated and locked in its rotated position to 40 present a new contact face to the cam surface, whereby the life of the brush is materially extended both as to the shoe, and also due to the fact, that the coil spring brush element is shifted so as to yield upon a new plane, resulting in eliminating the tendency 45 of the coil spring to crystallize.

With the above and other minor objects in view, the invention consists in certain peculiarities of construction and combination of parts as are hereinafter set forth with reference to the accompanying drawings and subsequently claimed.

In the drawings,

Figure 1 represents a face view of a timer embodying the features of my invention, 55 parts being broken away and in section to

more clearly illustrate details of construction.

Figure 2 is a side elevation of the same, partly in section, as indicated by line 2—2 of Figure 1.

60

Figures 3 and 4, a detailed sectional views through the brush holder, the same being indicated, respectively, by lines 3—3, and 4—4, of Figure 2, and

Figure 5, a detailed elevation of the two 65 piece cam.

Referring by characters to the drawings, 1 represents a rotary timer shaft, having secured thereto, the hub 2' of a wiper cam 2, the same being of the radial type. The 70 wiper cam 2 is formed from a single blank, having a foot extension *a*, which foot extension is seated within a longitudinally disposed recess that is formed in a lug *b*, that constitutes part of the cam hub 2'. The cam 75 is confined in its position with relation to the hub by means of a screw *c*, which screw, as shown in assemblage, is passed through an aperture formed in the body of the hub, the said screw being manipulated by a tool, 80 which may be introduced to the screw head, through an opening *d*, also formed in the hub shell, whereby assemblage is quickly effected.

It will be obvious, that owing to this construction, the fin or cam plate can be removed 85 for renewal, or cams of different designs can be inserted in connection with the hub, whereby the entire cam structure can be renewed without destroying or replacing the 90 hub portion.

It will be observed, also, that owing to the alignment of the longitudinal disposed recess in the hub lug, that the cam, when seated therein, is held against lateral play so 95 as to insure proper alignment.

A housing 4 is arranged concentrically about the shaft and adapted to be oscillated upon its bearing (not shown) whereby the spark may be advanced or retarded. The 100 housing is provided, in this instance, with four radial openings, suitably fitted with washers 5 of insulating material through which extends the shank portion 6 of a series of holders. Each holder shank is provided 105 with an inner collar 7, adapted to engage the inner surface of the washer 5 and the shank is firmly held in place by a nut 5' in threaded union with its corresponding threaded outer end of the shank, there being a binding nut 110

5" also run upon the end of the holder shank for connecting the conductor wire. Extending from the collar 7 of the holder is a threaded coupling nipple 8, which nipple is 5 adapted to receive the outer end of a closely coiled section of spring 9, the same constituting a brush.

The end of the coil spring has fitted therein, a metallic head 10, the same constituting 10 a solid contact shoe, that is preferably circular in cross section. The coils of the spring are approximately of the same pitch as the thread upon the coupling nipple, and hence, the brush tip can be readily screwed 15 to position and held firmly by the coupling nipple, it being understood that the free end of each coil spring carrying the shoe 10, is extended in the path of travel of the wiper cam 2, whereby make-and-break contact between the relatively rotative parts is effected. 20

In practice, it has been found that although many advantages result from the use of a brush of the coil spring type, it has developed that, while the coil spring is normally straight, it has a tendency to yield in opposition to force in all directions. Hence, when such type of brushes are engaged by the cam, the pliability will result in the tendency of the brush to sag backwardly under 25 certain conditions, and thus occasionally create a slight variation in the timing of the spark.

My present invention overcomes this tendency entirely, due to the fact that the problem has been solved by employing a guide for the brush, whereby said brush is positively held, so as to move in one plane only, or at a right angle to the line of travel of the cam.

40 The guide, in this exemplification of my invention, is formed from a single blank, including a web *e*, which is arranged parallel to the holder 6. The upper end of the web, is folded over to form a foot *f*, having a slot 45 therein, which slot is adopted to straddle and engage the shank portion 6 of the holder, being inserted between the juxtaposed insulated washer 5 and the collar 7. The lower end of the web has extended therefrom, and folded forwardly, a pair of guide wings *g*, between which guide wings the coil spring brush 9 extends and is thus held against lateral play, while freeing movement of the brush in a longitudinal direction 55 is had. It is understood that the brush guide, as a whole, is rotatorily adjusted about the axis of the holder shank, so as to position the wings in longitudinal alignment with the shaft or, in other words, such adjustment 60 will permit the contact brush to move back and forth at a right angle to the travel of the cam. Hence the brush thus being held against lateral movement will always effect a contact at the same high point of the cam 65 in its cycle.

It will also be observed, that when a "fin cam" or lug is used, in place of a side swiping cam, the guide can readily be rotated 90° from the before mentioned location, so as to permit movement of the brush in a 70 plane parallel to the rotation of the shaft.

Owing to this adjustability, it is also observed that after the brush has been used for a predetermined time and the coil springs have been flexed upon a constant plane to a 75 point where deterioration might result, the coil spring brush can be rotated to change the line of flexure. This adjustment of the parts will also present a new contact face of the brush shoe 10 to the cam, whereby 80 proper timing is insured, which timing may be varied in instances where the shoe would flatten or wear.

While I have shown and described one simple exemplification of the brush guide, 85 obviously I may vary the structural feature of the guide within the scope of the plane as they will hereinafter be interpreted by those skilled in the art.

I claim:

1. A timer comprising a relatively rotated cam and contact brush, the same including a normally straight coil sectional spring, capable of yielding in all directions, and a 90 guide for directing movement of the coil spring brush in a single plane.

2. A timer comprising a relatively rotated cam and contact brush, the same including a normally straight coil sectional spring, capable of yielding in all directions, and a guide 100 for directing movement of the coil spring brush in a single plane only.

3. A timer comprising a housing, a rotatory cam mounted in the housing, holders extending inwardly from the housing, coil 105 spring brushes carried by the holders engageable with the cam, and guides extending inwardly from the housing associated with the holders, the guides having side wings for encasing the brushes, whereby the 110 same are held against movement except in one direction.

4. In a timer mechanism having a rotatory cam, a housing mounted thereabout, holders extending through the housing, coil 115 springs secured to the holders, the same constituting contact brushes for engagement with the cam, and means associated with the holders and housing for limited movement of the coil spring brushes except in one direction. 120

5. A timer comprising a rotatory cam, a housing associated with the cam, collared holders extending through the housing, coiled spring brush sections secured to the 125 holders and extending into the line of travel of the cam, guides for the coil spring brush sections, the guides being formed with apertured feet for engagement with the holders, whereby they are frictionally held in posi- 130

tion, the said guides having wings encasing the coil spring brushes, whereby they are held against movement, except in one direction.

- 5 6. In a timer having a housing, contact brushes carried thereby, a rotatory shaft, a hub carried thereby, and a radially disposed cam plate detachably secured to the hub, a one piece guide for the contact brushes, the
10 same including a web having a slotted foot extension, whereby the guide is attached,

the web being provided at its opposite end with parallel guide wings and a renewable cam for brushes comprising a hub including a separable cam plate having a foot extending therefrom, and means for securing the cam plate to the hub. 15

In testimony that I claim the foregoing I have hereunto set my hand at Milwaukee, in the county of Milwaukee and State of Wisconsin. 20

ADAM W. KAUFMAN.
